CLASSIFYING PROCESS AND APPARATUS

Jean Albert Brusset, Blairmore, Alberta, Canada

Application October 1, 1941, Serial No. 413,218

8 Claims. (Cl. 209—173)

The present invention relates to processes and apparatus for separating mixed granular materials of different specific gravities according to their specific gravities, and particularly into three or more clean-cut products, by means of a novel flotation bath made up of a suspension of solid material in water.

It has in the past been found relatively easy to make two-product separations, (one "float," and one "sink") in liquids or suspensions. In attempts to split the "sink" into two further products of different specific gravities the prior investigators attempted to effect the further separation by creating rising currents in the bath, it having been the theory that such currents would have more lifting action on the lighter material in the "sink," and would be expected to carry this lighter material away to a convenient means of gathering and conveying. However, it has been found that this theory does not work out in practice, because these currents select, among the particles of the "sink," not only those particles of lesser specific gravity but also those of smaller size regardless of specific gravities which offer a relatively greater surface to the action of those currents. The result is that the material carried off by such accessory currents is a mixture of large and small particles of material of intermediate specific gravity, plus small particles of the heavier specific gravity material. Conversely, there remain in the heavier material, separated as "tailings" or "refuse," the larger particles of the intermediate material. Thus a clean-cut separation of the "sink" into "intermediate" and tailing or refuse has not been possible with prior processes using accessory currents to divide the "sink."

The process of the present invention eliminates the use of any currents in the bath for the selection of refuse and middlings, and thus avoids the danger of impure products, as will be seen below.

A primary object of the invention is to obtain a perfect separation of three very clean-cut products (concentrate, middlings and tailings, or, in the case of coal, clean coal, middlings and refuse) by the use of one unique bath, of appropriate specific gravity, of a suspension of finely divided solid material in water.

An important object of the invention is the provision of an improved novel flotation medium for the separation of a mixture of materials of different specific gravities by a sink and float process.

It is an object of the invention, also, to pro-

vide novel apparatus for use in effecting this sink and float process.

The new flotation medium of the invention consists essentially of an aqueous suspension of finely divided limestone rock, 90% minus 150 mesh, in sufficient concentration to provide a medium of required specific gravity. The limestone rock should be as pure as possible, that is, especially free from shales and clay. Ground limestone rock makes very stable suspensions in water, and all specific gravities of flotation medium, between 1.30 and 1.70, can readily be provided without undue viscosity of the medium at the higher values.

15 By grinding the limestone so that 90% passes a 150 mesh screen there is a small percentage of larger particles which settle more rapidly, thus maintaining a slightly higher specific gravity of medium adjacent the bottom of the bath, which circumstance is an advantage in the present process as it expedites separation of the "sink" into two final products.

20 Finely divided limestone rock as the solid ingredient of the suspension medium possesses a number of advantages over previously proposed media: thus, it is readily available almost everywhere; it is easily crushed to the required mesh; it is not abrasive on the machinery; it remains readily in suspension; it does not stick to the finished products and is easily washed off of them; and it is easily recovered from the wash water by cycloning so that recycling is facilitated.

25 In one aspect, the process of the present invention consists essentially in introducing a mixture of solid particles of lighter and heavier specific gravities into a bath of the aqueous suspension of finely divided limestone having a density adjusted to float the lighter but not the heavier particles, and separately removing lighter particles from the top and heavier particles from the bottom of the bath.

30 I have found that said finely divided limestone suspension may be used as the suspension medium in a modification of the aforesaid process, by which a mixture of lighter, intermediate, and heavier particles can be separated into its components, as follows: The density of the bath of suspension medium (e. g., aqueous suspension of finely divided limestone) is so adjusted that the light particles float thereon while the intermediate and heavy particles sink therein at varying rates of speed (preferably, so adjusted that the intermediate particles sink only very slowly 35 through the bath); after the heavy particles

have sunk through a substantial depth of the bath there is imparted to them a step-by-step translational movement, to one side or end of the container, by means of a longitudinally reciprocating sloping stepped deck (preferably, a longitudinally reciprocating sloping stepped deck whose forward motion, in the direction of the upper end thereof, is slower than its backward motion), whereby the sunken heavy particles are collected substantially at one line (i. e., the top end of the stepped deck) at which line the so-collected heavy particles are separately withdrawn from the container and suspension. The intermediates simultaneously are concentrated at the low end of the stepped deck and are continuously or intermittently withdrawn, admixed with suspension medium, at the latter. The light particles are, of course, separately withdrawn at the top of the bath of suspension medium.

While the aforesaid aqueous suspension of finely divided limestone is admirably suited for use in the 3-way separation just described the latter may be carried out with the use of one or another of the prior art suspension media.

After the removal of the separated components, the latter are washed to remove suspension medium therefrom, and the suspension medium is reformed for reuse in a repetition of the process. From the viewpoint of the suspension medium, the 3-way separation process is a cyclical one, in which the steps constituting one cycle are as follows:

1. Suspension medium, of controlled predetermined density is fed to a separatory vessel to maintain therein a bath of predetermined depth;
2. Suspension medium, plus separated particles of the mixture undergoing treatment, is removed from the bottom of the separatory vessel;
3. Withdrawn suspension medium is removed from said separated particles by washing, thereby producing diluted suspension medium;
4. The so-diluted suspension medium is partially dewatered (the resulting water being useful for the washing step 3);

5. Fresh suspension medium of predetermined density is reformed from the dewatered suspension obtained in step 4 plus additional water, and used as the suspension medium in step 1.

In step 3 of the cyclical process, the withdrawn material is washed in a plurality of stages, in the first of which I employ as washing liquid the "water" obtained by partially dewatering the diluted suspension medium which is the product of that step; in a second stage of which I employ as washing liquid filtrate from the said "water"; and in the final stage of which I employ as washing liquid fresh make-up water. The three wash waters are combined and in step 4, are partially dewatered by treatment in a cyclone separator yielding (a) thickened suspension medium and (b) a "water" contaminated with a relatively small amount of the solids of the original suspension medium; which latter is divided into two portions one of which is used as initial washing liquid and the other of which is further clarified by filtration for use as intermediate washing liquid. The filter cake, consisting essentially of solids of the original suspension medium, may be and preferably is added to the thickened suspension medium obtained from the cyclone separator.

In carrying out step 5 of the cyclical process, I feed streams of thickened suspension medium and water (specifically, the partially clarified water from the cyclone separator) to a mixing ves-

sel, continuously automatically determine the specific gravity of the resulting mixture, and continuously automatically control the rates of feed of thickened suspension medium and water to said mixing tank to maintain the specific gravity of the mixture within narrow predetermined limits, as will be described more fully hereinafter.

The process and apparatus used in practicing the same will be described in greater detail with reference to the accompanying drawings which illustrate a preferred embodiment of the invention and in which:

Fig. 1 is a diagrammatic view of a plant embodying the invention;

Fig. 2 is a vertical sectional view of the main separating tank;

Fig. 3 is a sectional view approximately on the line 3—3 of Fig. 2;

Fig. 4 is an enlarged diagrammatic view of the suspension feed controls, and

Fig. 5 is a detail of the mounting of the submerged deck.

The main classifying tank 5, which will vary in size depending on the capacity desired, preferably is a metal tank having at one end a feed bin 6 which discharges onto a slanting feeding shelf 7 and disposed at an angle of about 30° at its lower end within the tank 5. An endless raking conveyor 8, running over sprockets 9 and 10 mounted at opposite ends of the tank, rakes the mixed material off of the feed shelf 7 as the rakes 11 of the lower flight thereof begin their travel through the tank, and conveys the lighter materials which float on the separating medium to the other end and out over a discharge lip 12 at the end opposite the feed bin 6. The rakes 11 of the conveyor are made of perforated sheet iron and travel at a slow rate of speed through the upper portion of the bath so that they cause no undue agitation which might result in imperfect separation.

The heavy and intermediate materials of the mixture supplied through feed bin 6 sink through the bath between the lower edge of feed plate 1 and an inwardly slanting deflector plate 13 mounted on the inside of tank wall 14 opposite plate 1 to a reciprocating deck or screen 15. The deck 15 is mounted at an angle of about 5° to 10° to the horizontal with its lower end beneath the plate 1, the amount of the slope being dependent on the character of the material being separated, and is supported on arms 16 which are set perpendicular to the plane of the deck so that the motion of the deck is practically longitudinal in its own plane without any appreciable vertical or jiggling component.

The upper ends of the supporting arms for the reciprocating deck 15 terminate in a spindle 17 upon which is mounted a heavy block or bushing 18 of rubber clamped between plates 19 by a nut 20. Steel collars 21 carried on depending brackets 22 secured to the side frames 23 of the deck 15, clamp the rubber bushings 18 to make the connection between the arms and the deck. Similar rubber blocks or bushings 24 mounted on the lower ends of the arms 16 are clamped between collars 25 carried on brackets 26 secured to a stationary member 28 mounted between the side walls of the tank 5. When the deck 15 is reciprocated by the means described hereafter the rubber blocks or bushings 18 and 24 yield sufficiently to allow the motion of the screen to take place and act as bearings not requiring lubrication. This is important because

all of these parts are immersed in the suspension medium.

Reciprocating motion is imparted to the deck 15 by a drive rod 29 which extends through the end wall 30 of the tank, its passage and motion therethrough being sealed by a rubber diaphragm 31. The inner end of the rod 29 is provided with a rubber bushing 32 which is clamped by a collar 33 carried by a bracket 34 fastened to the deck 15. A roller 35 mounted on the outer end of the rod 29 bears on a rotary cam 36, the profile of which is formed so as to advance the deck slowly toward its upper end and permit a quick return motion. The quick return motion of the deck is partially caused by the resilience of the rubber block connections at the ends of the supporting arms and in addition is effected by resilient coil springs 37 acting between the upper end of the upper set of arms 16 and a stationary part of the tank 5. The driving cam 36 for imparting reciprocating motion to the deck is driven at the rate of about 120 revolutions a minute.

The supporting surface of the deck 15 is preferably formed of sheet iron perforated uniformly over its area with $\frac{1}{4}$ or $\frac{1}{2}$ inch holes 38 and is corrugated or crimped into stepped formation to provide upwardly sloping steps 39 terminating in steep faces or shoulders 40 which face toward the upper end of the deck. The upper end of the deck extends beneath the lower end of the deflector plate 13 and terminates over the upper end of a discharge channel 41. The lower end of the deck 15 extends to a point adjacent the wall 30 under the plate 13 and over the edge of a discharge channel 42.

In the course of operation, the lighter material, or "float," is evacuated from the box by conveyor 8 over the lip 12. The heavier material sinks between plates 1 and 13 and toward deck 15. The lighter portion of that material, or "middlings," which has a specific gravity fairly close to that of the bath, sinks more sluggishly than does the heavier material, which latter tends to reach and rest upon the deck 15. Due to the fact that the deck 15 moves quickly rearwardly, that is, in the direction of the lower end thereof, the heavy material will, because of its inertia, slide forward along the slightly inclined upper faces 39 of the steps, but during the forward and slower motion of the deck, the steep faces 40 of the steps will catch the heavy material and advance it toward the upper end of the deck. The heavy material will thus move step by step towards plate 13 along the deck, and finally will be discharged from the upper end of the deck into passage 41 under plate 13.

The intermediate particles or "middlings," the gravitational motion of which is too sluggish in the heavy medium to cause the same to be held in contact with the stepped screen, will move in the opposite direction, that is to say, towards the right-hand side of the tank 5, under the influence of gravity alone, since the right-end of the deck is lower than the left end. The loosening of the mass of middlings by the motion of the screen will accelerate this displacement under the influence of gravity. The middlings travel past the lower end of the deck 15 and are deposited in a transverse channel 42, the edge of which is overlapped by the end of the deck.

It will be seen that as the specific gravity of the suspension is practically equal to that of the middlings, the latter are subjected to a resultant force which is practically nil; so that if they

ever come in contact with the reciprocating deck, they will bounce away from it like a shuttlecock from a racket.

Worm-conveyors 43 and 44 collect the heavy product at the lower extremity of passage 41, and the middlings in the channel 42 at the lower extremity of deck 15, respectively, and separately deliver them to two endless elevators 45 and 46 respectively which have common shafts and drives. Worm-conveyor 43 also collects and conveys whatever small heavy particles of material have fallen through the perforations of deck 15, and the portion of the solid medium which has slowly settled to the bottom of the separating tank 5.

As may be seen from the above, the separation of the mixture into three products does not make use of any currents whatever. The only principles involved are those of sink-and-float separation in a bath of appropriate specific gravity, plus separation of the "sinks" into two products by selective frictional action of the reciprocating stepped deck on the heavier particles of the "sink."

The clean coal discharged over the lip 12, the middlings discharged into the channel 42 and the refuse discharged into the channel 41 together with the fine heavy material and settled suspension which finds its way into channel 47 are delivered by suitable conveyors 48-48', 46 and 45, respectively, to washing screens 49, which for convenience are preferably arranged side by side. As the separated materials pass over the screens 49 they are washed successively by water from other stages of the process and finally by clean make-up water supplied through sprays 50, 51 and 52, respectively.

The spent wash water with the medium washed from the separated materials on screens 49 is caught by collectors 53 beneath the screens and flows therefrom to a tank 54. A pump 55 delivers the dilute suspension from tank 54 through pipe 56 tangentially at high speed into a cyclone separator 57 where the bulk of the solids of the suspension medium are separated from the wash water. In order to remove fine particles of the constituents of the mixture which find their way through the screens 49 and flow with the dilute medium to tank 54, small quantities of flotation reagents (oil in the case of coal) and air are by means of injector 58 continuously injected into pipe 56 between pump 55 and the cyclone separator 57 to produce in the cyclone a flotation reaction which causes the entrained particles of the mixture to float to the surface and flow to tank 59 in the flotation foam carried on the water discharged from the cyclone to said tank. A rotary sludge extractor 60 skims the foamy sludge from the surface of the water in tank 59 into a discharge launder 61 mounted thereon. The water overflowing from the cyclone separator 57 to the tank 59 is relatively free of solids of the suspension medium.

A portion of the water from the cyclone separator is bled off of the line 62 leading to tank 59 and passed to a vacuum filter 63 where it is clarified of all suspension medium. The clarified water from the vacuum filter is fed to the intermediate set of washing sprays 51 over the screens 49.

Under the action of centrifugal force in the cyclone separator 57 the particles of limestone of the suspension medium separate from the water and gather in the bottom of the cyclone which is closed by a soft rubber pad 64 mounted on the end of a pivoted lever 65 and balanced by a counter-

weight 66 adjustable along the other end of the lever. The position of the counterweight 66 is adjusted to balance the pressure of the liquid and solids above the valve pad 64 until a desired minimum concentration of solids which it is desired to extract from the cyclone exists above the valve pad. When the concentration of solids in the bottom of the cyclone exceeds the desired minimum value for which the counterweight is set, the pressure above the valve pad overcomes the counterweight to open the valve and the thickened suspension flows down into the high specific gravity tank 67. When the flow has continued to the point where the concentration in the cyclone decreases below the desired minimum, the counterweight will close the valve 64 and the flow will be cut off until the concentration again builds up. Thus the tank 67 is kept supplied with concentrated suspension from the cyclone.

Concentrated suspension from the tank 67 flows through pipe 68, equipped with a regulating valve 69, to a mixing tank 70 where it is mixed with water supplied through pipe 71 equipped with a regulating valve 72, from water tank 59. From the mixing tank 70 the reformed suspension medium of desired specific gravity is pumped through pipe 73 by pump 74 to the main separating tank 5 to maintain the level of medium therein and to insure maintenance therein of the proper concentration of the suspension medium.

The delivery of concentrated suspension and water to the mixing tank 70 is regulated so as to maintain at a constant predetermined value the specific gravity of the suspension therein which is fed to the main treatment tank 5. This regulation is effected by a specific gravity control system generally designated 75. This system includes a container 76 which is constantly supplied with suspension bled off of the feed pipe 73 at 77. The container is provided with a small drainage opening 78 in the bottom thereof and an overflow 79 at the top so as to maintain a constant level of suspension medium in the container 76 and prevent building up the concentration therein.

A pipe 80, bent to U-shape, is immersed in the suspension in the tank 76 so that its horizontal portion 81 is about 50 inches below the level of the suspension. A series of small holes 82 are provided in the lower side of the immersed horizontal portion 81 of the U-shaped pipe. One end 83 of the pipe 80 is connected to a diaphragm pressure gauge 84 and the other end 85 is connected to a constant pressure air tank 86 which is supplied with compressed air from a supply pipe 87 through a reducing valve 88 which is set to maintain a constant pressure of 100" W. G. in the tank 86. A series of small orifices 89 in the connection from the tank 86 to the U-shaped pipe 80 provides for low volume feed of air at constant pressure to the pipe.

The pressure of air in pipe 80 is always lower than 100" W. G. because air is fed through orifices 89 at a very slow rate and as soon as the pressure in pipe 80 reaches the value corresponding to the head of suspension above holes 82, the air escapes through those holes and bubbles up to the surface of the bath. As a result, the pressure inside pipe 80 is always equal to that created by the height h (in inches) of suspension existing above the level of holes 82, or: $P = h \times S$ where S is the specific gravity of the bath. As h is kept constant, pressure P directly measures the specific gravity of the suspension in the mixing tank 70. The pressure in the pipe 80 is registered by diaphragm pressure-gauge 84, which

may also be made into a recorder if it is desired to keep a close check on the operation of the treatment tank.

The gauge 84 controls the specific gravity in mixing tank 70 in an automatic manner. When the specific gravity increases above the desired value, for which the diaphragm is kept at its average position by an adjustable spring 90, the diaphragm is lifted, and through a set of light arms and rods 91 tilts to the left mercury switch 92, thereby starting electric motor 93 which through arm 94, link 95 and lever 96 on valve shaft 97 operates valves 69 and 72 from position #1 to position #2. Valve 72, now fully open, admits more water from tank 59 to the mixing tank, while valve 69 which controls the flow of heavy suspension from tank 67 is nearly closed. Thus the specific gravity of the suspension in the mixing tank is quickly reduced. As soon as the specific gravity is back to normal, the spring pulls the diaphragm back and so throws open the switch 92, thereby deenergizing motor 93. Valves 69 and 72 then are brought back to position 1 by counterweight 98 on lever 96 and from then on deliver a greater proportion of heavy suspension than water to the mixing tank, thus tending to increase the specific gravity. By this means, the specific gravity of the suspension in tank 70 will continually fluctuate within very narrow limits around the desired value, without ever exceeding those limits. For instance, for coal-washing, if a gravity of 1.50 is desired, the range of variations will be from 1.49 to 1.51, which amounts to keeping an average of 1.50.

All of the tanks 54, 59, 67 and 70 are provided with agitators 99 to prevent settling out of the solids suspended in the liquids maintained in or passing through the tanks. Make-up limestone dust of the proper fineness is fed to the tank 67 by a feeder 100 to replace the small amount inevitably carried off with the separated materials and clean make-up water is supplied to the final wash spray 52.

While a preferred process and apparatus for use in practicing the same has been described and shown by way of illustration, it will be understood that various modifications in the details thereof may be resorted to without departing from the spirit of the invention within the scope of the appended claims.

I claim:

1. The process of separating a mixture of light, intermediate and heavy solid particles into its components according to their specific gravities, which comprises introducing the mixture into a body of suspension medium comprising finely ground solid particles in water, maintaining the suspension medium at a density to float only the light particles of the mixture whereby the intermediate and heavy particles tend to fall by gravity in a downward path through the suspension medium, imparting a sidewise propelling movement to the heavy particles across the line of their gravitational path, at a zone in said body of suspension medium intermediate the top and bottom thereof, toward one side of said body, while avoiding creation of vertical currents in the suspension and while simultaneously permitting the intermediate particles to move by gravity below such zone of sidewise propelling movement, segregating the so-propelled heavy particles at said side of the body of suspension medium and thereafter removing them from said body, and removing the intermediate particles from the body of suspension medium at a loca-

tion below that at which said heavy particles are segregated.

2. The process of separating light particles, intermediate particles and heavy particles from each other in a mixture thereof in the presence of a medium comprising a suspension of finely divided solid particles in liquid, which comprises maintaining a body of the medium at a density to float the light particles only whereby the intermediate and heavy particles fall by gravity through said suspension medium at varying rates of speed, feeding the mixture to the upper part of said body of suspension medium, removing floated light particles from the surface of the suspension medium, permitting the intermediate and heavy particles to fall by gravity in a downward path through the suspension medium, at a zone in said body of suspension medium intermediate the top and bottom thereof, imparting to the heavy particles only a sidewise step-by-step translational movement to one side of said body of suspension medium while simultaneously permitting the intermediate particles to progress by gravity past such zone of translational movement, segregating heavy particles at said side thereof, and thereafter removing them from said body of suspension medium, and removing intermediate particles from said body of suspension medium at a location below that at which said heavy particles are withdrawn.

3. The process of separating light particles, intermediate particles and heavy particles from each other in a mixture thereof in the presence of a medium comprising a suspension of finely divided solid particles in liquid, which comprises maintaining a body of the medium at a density to float the light particles and nearly to float the intermediate particles, feeding the mixture to the upper part of said body of suspension medium, removing floated light particles from the surface of the suspension medium, permitting the intermediate and heavy particles to fall by gravity in a downward path through the suspension medium, at a zone in said body of suspension medium intermediate the top and bottom thereof, imparting to the heavy particles only a sidewise step-by-step translational movement to one side of said body of suspension medium while simultaneously permitting the intermediate particles to progress by gravity past such zone of translational movement, segregating heavy particles at said side thereof, and thereafter removing them from said body of suspension medium, diverting the intermediate particles along a downwardly inclined path toward another side of said body of suspension medium than that to which the heavy particles are moved, and removing intermediate particles from said body of suspension medium at said other side of the latter and at a location below that at which said heavy particles are withdrawn.

4. In apparatus for separating mixtures of solid materials of different specific gravities by the float-and-sink method involving use of a suspension medium essentially consisting of a suspension of finely divided solid material in a liquid and having a density adapted to float one but not all of the constituents of the mixture to be separated, a tank containing a body of such suspension medium, a sloping deck mounted within the lower portion of said tank and having a stepped surface providing spaced shoulders facing the higher end thereof, means for mounting said deck for a reciprocating motion substantially in the plane thereof, means for reciprocating

ing said deck with a differential motion in which said deck is moved faster toward the lower end than toward the higher end thereof, means for removing heavy material progressing over the higher end of said deck, means for removing intermediate material gravitating toward the lower end of the said deck, and means for removing light material floated on the surface of the suspension medium in the tank.

10 5. In apparatus for separating mixtures of solid materials of different specific gravities by the float-and-sink method involving use of a suspension medium essentially consisting of a suspension of finely divided solid material in a liquid and having a density adapted to float one but not all of the constituents of the mixture to be separated, a tank containing a body of such suspension medium, a sloping deck mounted within said tank beneath the surface of such body of suspension medium for reciprocation substantially in its own plane, said deck having a stepped surface providing spaced shoulders facing the higher end thereof, means for imparting reciprocating motion to said deck, and separate means for removing separated materials adjacent the higher and the lower ends of the deck.

6. In apparatus for separating mixtures of solid materials according to specific gravity wherein the materials are separated by selective action 30 of a suspension medium of finely divided solid in liquid in a separating tank and wherein separated materials are washed to remove suspension medium therefrom and the wash waters are clarified to produce a supply of thickened suspension medium and water, and thickened suspension medium and water are mixed in regulated quantity to form a suspension medium of desired specific gravity for replenishing the supply in the tank, a mixing tank, means for delivering reformed suspension medium of desired specific gravity from the mixing tank to the separating tank, a control receptacle, means for continuously passing a portion of reformed suspension medium from said mixing tank to said control receptacle to maintain a constant level 40 of suspension medium therein, a U-shaped pipe immersed in said control receptacle having perforations below the level of medium therein and connected at one end to a pressure responsive means, means for supplying air under constant pressure to said pipe through the end thereof opposite to that connected to said pressure responsive means, and means under control of said pressure responsive means for controlling the feed of thickened medium and liquid to said mixture tank.

7. The process of separating light particles, intermediate particles and coarse and fine heavy particles from each other in a mixture thereof in the presence of a medium comprising a suspension of finely divided solid particles in liquid, which comprises maintaining a bath of the medium at a density to float the light particles and nearly to float the intermediate particles, feeding the mixture into said bath of suspension medium, removing floated light particles from the surface of the bath of suspension medium, permitting the intermediate and heavy particles to fall by gravity in a downward path through the suspension medium at varying rates of speed, at a zone in said body of suspension intermediate the top and bottom thereof, imparting to the coarse heavy particles only a sidewise step-by-step translational movement to one side of said body of suspension medium, while permitting the

fine heavy particles to continue to sink through the suspension medium without substantial translational movement and simultaneously diverting the intermediate particles, under the influence of gravity, toward another side of said body of suspension medium than that to which the coarse heavy particles are moved, segregating the coarse heavy particles at the side of said body to which they are moved and thereafter removing them from said body, segregating the intermediate particles at said other side of said body and thereafter removing them from the latter, withdrawing suspension medium and associated fine heavy particles from the bottom of said bath, and separating fine heavy particles from the withdrawn suspension medium.

8. Apparatus for separating a mixture of solid materials of different specific gravities according to the float-and-sink method involving the use of a suspension medium essentially consisting of a suspension of finely divided solid material in

a liquid which suspension medium is maintained at such a density that at least one but not all of the constituents of the mixture sinks therein, which comprises in combination a separating tank containing a body of such suspension medium, means for delivering the mixture to be separated to the upper part of the body of suspension medium, a sloping deck mounted within said tank for reciprocation substantially in its own plane, said deck having a stepped upper surface providing spaced shoulders facing the higher end thereof, means mounted in said tank above said deck for diverting sinking particles onto said deck, means for imparting reciprocating motion to said deck, segregating channels associated with the higher and lower ends of said deck to receive materials discharged over said ends, and separate means for withdrawing segregated materials from said segregating channels.
